Atty.*

UNITED STATES PATENT OFFICE.

ERNST PAUL LEHMANN, OF BRANDENBURG-ON-THE-HAVEL, GERMANY, ASSIGNOR TO THE FIRM ERNST PAUL LEHMANN, PATENTWERK, OF BRANDENBURG-ON-THE-HAVEL, GERMANY.

GYROSTATIC TOY.

Application filed December 22, 1926, Serial No. 156,469, and in Germany January 23, 1926.

This invention relates in general to gyrostatic toys or toys driven through the agency of a fly-wheel that is started turning or spinning by hand. The invention 5 relates more particularly to vehicular toys of this kind as for example toy aeroplanes and a feature of it is that the motion of a fly-wheel or gyrostat mounted on a vertical or approximately vertical axis is transferred 10 through toothed wheels to the travelling wheel axle of the machine.

The invention is illustrated in the drawing in which

Fig. 1 is a sectional elevation of a constructional form in the shape of an aeroplane,

Fig. 2 is a top view of Fig. 1, and

Fig. 3 is a bottom view of the principal part of the machine.

20 The machine has a body portion 1, a plane 2 and a supporting member 3 attached to the plane and adapted to support the driving member or rotor 9. Attached to the supporting member 3 are downwardly extending lugs 6 in which is journalled the axle 5 on which are fixed the travelling wheels 4. Also fixed on the axle 5 is a toothed wheel 7 with overhanging teeth that engage with the teeth of a second toothed 25 driving wheel 8 which is fixed on a vertical spindle 9. The bottom conical end of this spindle is journalled in a recess 10 in the sheet metal supporting member 3 and about midway between its two ends the spindle 30 9 is journalled in a bearing or collar 11 formed integral with the plane 2. The spindle 9 is provided with a fly-wheel or the like. Projecting from the front end of the machine, is a shaft 13 on which rotates a propeller 12 which is, however, not

necessary for the operation of the toy. At its tail end the machine is provided with a small additional travelling wheel 14 that facilitates the travel of the machine when the rotor or gyrostat 9 is spun round. 45

What I claim is:—

1. A toy in the form of an aeroplane comprising a vehicular body, a horizontal axle attached to said body adjacent the front end thereof, travelling wheels on said axle, 50 a toothed wheel with lateral overhanging teeth mounted on said axle, a vertical driving spindle mounted in the vehicular body, a driving toothed wheel mounted on said vertical spindle and having its teeth in mesh with said first toothed wheel, and a fly-wheel mounted on the vertical driving spindle, the said driving spindle being accessible from the outside, so that it may be rotated by hand together with the flywheel. 55

2. A toy in the form of an aeroplane comprising a body portion, a horizontal plane connected transversely of the top and at the forward end of the body portion, a vertical spindle mounted centrally through said plane, a supporting member connected to and arranged beneath said plane for supporting the bottom end of said spindle, an axle mounted transversely of the supporting member, a toothed wheel on said spindle, a second toothed wheel on said axle and engaged with the teeth of the first toothed wheel, supporting wheels for all of the parts mounted on said axle, a fly-wheel mounted on the upper projecting part of the spindle 70 and arranged above said plane, substantially as and for the purposes set forth. 75

In testimony whereof I have signed my name to this specification.

ERNST PAUL LEHMANN.
